(57) **CLAIM**

The ornamental design for an inhaler spacer, as shown and described.

DESCRIPTION

FIG. 1 is a perspective view of the inhaler spacer of my new design;

FIG. 2 is a front elevation view thereof;

FIG. 3 is a back elevation view thereof;

FIG. 4 is a left elevation view thereof;

FIG. 5 is a right elevation view thereof;

FIG. 6 is a top plan view thereof; and,

FIG. 7 is a bottom plan view thereof.

The broken lines in the drawings depict portions of the inhaler spacer that form no part of the claimed design.

1 Claim, 7 Drawing Sheets
